United States Patent Office

Des. 193,820
Patented Oct. 9, 1962

193,820

CHECKOUT COUNTER

Paul Hittinger and James M. Steinke, Dayton, Ohio, assignors to The National Cash Register Company, Dayton, Ohio, a corporation of Maryland

Filed Oct. 5, 1961, Ser. No. 67,002

Term of patent 14 years

(Cl. D80—2)

FIG. 2

FIG. 3

FIG. 4

FIG. 1 is a rear perspective view, taken from the left side, of a checkout counter showing our new design;

FIG. 2 is a perspective view taken from the right side and rear thereof;

FIG. 3 is a fragmentary left side elevational view thereof;

FIG. 4 is a rear elevational view thereof, the cash register keyboard being omitted for convenience of illustration; and

FIG. 5 is a front elevational view thereof, the cash register keyboard being omitted for convenience of illustration.

The dominant features of our design reside in the full-line portions of the drawing.

We claim:

The ornamental design for a checkout counter, as shown and described.
